UNITED STATES PATENT OFFICE.

GEORGE T. VAN HORN, OF NUTLEY, NEW JERSEY.

GARAGE-DOOR OPERATOR.

Application filed April 7, 1925. Serial No. 21,307.

My invention relates more particularly to a power operated mechanism for opening and closing the garage doors without getting out of the car, both for entering and when leaving the garage, and is an improvement over the devices of my Patents, Nos. 1,388,533 of August 23, 1921, and 1,436,122 of November 21, 1922.

One object of my improved mechanism is to provide a weight operated drum for operating the mechanism for opening and closing the doors, whereby by winding up the weights power is provided for a plurality of opening and closing operations of the doors.

15 A further object is to provide a crank arm member rotating under the driving action of the weight driven drum for opening and closing the doors, the crank arms being under the control of an escapement dog for intermittently releasing the crank arm member, and for engaging said member to stop rotation thereof.

20 A further object is to provide a plurality of manually operable cable connections to the escapement dog for releasing the door operating crank arms, one of which is preferably carried underground to a post located in front of the garage, the post being provided with a hinged member operatively connected with the cable, adapted to be operated by anyone in the car to open the garage doors without the necessity of getting out of the car.

25 A further object is to provide one of the cables operating the escapement dog with an extension, which may be held in the hand of the operator when taking the car out of the garage to operate the escapement dog and permit rotation of the crank arm member, to close the doors. This last mentioned operating cable for the escapement dog is preferably provided with a weight at the rear end thereof for snapping or drawing it back into the garage, after it has been operated by a person in the car for closing the doors, when the car has been moved out far enough to clear the latter.

30 A further object is to provide resilient cushion devices on the crank arm member for cooperation with the escapement dog as a shock absorber to reduce jar and vibration when rotation of the crank arm is stopped by engagement with the dog.

35 My improvement, as here shown, is more particularly adapted for operating a pair of doors closing the garage and, since one of

the doors is usually provided with a weather strip overlapping the joint between the closed doors, it is required that the door without the weather strip should be closed 60 ahead of the other one to prevent interference of the weather strip. Therefore, a further object of my improvement is to provide an extensible connecting link for one of the doors to facilitate closing it ahead of 65 the door carrying the weather strip.

I have shown in the accompanying drawings, one form of my improved garage door operating mechanism, more particularly adapted for a single garage with double 70 doors. Fig. 1 shows a top plan view of my door operating mechanism, with the top of the garage removed; Fig. 2 is a fragmentary sectional view of certain details, the section being taken on the line 2—2 of Fig. 1; Fig. 75 3 is a longitudinal sectional view of one of the connecting rods, showing the extensible feature; Fig. 4 is a cross sectional view in elevation of the garage, looking toward the doors, the section being taken on the line 80 4—4 of Fig. 1; Fig. 5 is a fragmentary vertical section at the joint between the doors on the line 5—5 of Fig. 4; Fig. 6 is a vertical sectional view of the drum and bearing plates associated with the crank member; 85 Fig. 7 is a plan view of the lower bearing of the drum, taken on the section line 7—7 of Fig. 6; Fig. 8 is a broken view in section on the line 8—8 of Fig. 6, showing the ratchet drive for the crank arms; Fig. 9 is a fragmentary plan view showing the doors in 90 open position; Fig. 10 is a vertical sectional view through the post located in front of the garage, for operating the mechanism from the car; Fig. 11 is a transverse vertical 95 section of the post on the line 11—11 of Fig. 10, and Fig. 12 is a detail view of the weight suspension for power operation of the drum.

Referring to the drawings, the garage is represented at 1, which, in the present instance is provided with double doors 2 and 3 hinged at 4 to open horizontally outward. The door 3 is preferably provided with a weather strip 5 to cover the crack between the doors, when in closed position, as shown 105 in Fig. 1, of the drawings. The respective doors 2 and 3 are connected by means of links or connecting rods 6 and 7, with a pivot pin 8 mounted near the outer end of a crank arm 9, the opposite ends of the links being pivotally connected to brackets 10, secured to the respective doors at predetermined points 110

near their top edges, substantially as shown in Fig. 4 of the drawings.

The length of the crank arm 9 and the position of attachment of the brackets 10 to the doors is such that upon a half rotation of the crank arm 9, the doors will be fully opened, substantially as shown in Fig. 9 of the drawings. Obviously, when the crank arm 9 is rotated back to the position shown 10 in Fig. 1, the doors will again be closed.

In view of the fact that the door 3 carries the weather strip 5 the other door 2 must be closed slightly ahead of the door 3. This is accomplished by shortening the connecting rod 6 to the door 2 and inserting 15 therein an extensible joint 11, provided with a telescoping tubular extension 12 completing the full length of the connecting rod. The telescoping member 12 and the joint 11 are connected together by a pin 13 and slot 14 which permits extension of the rod 6-12 to the full length required between the crank pin 8 and the door 2, when 20 crank arm 9 is on dead center and the door 25 is closed, as indicated in Fig. 1. To shorten the rod 6-12 during the closing operation, a spring 15 is connected between the pin 13, which is secured in the joint member 11, and a pin 16 secured in the telescoping 30 member 12, substantially as shown in Fig. 3 of the drawings. The rod end 17 secured to the tubular telescoping member 12 is pivotally mounted in the bracket 10, mounted on the door 2 as shown in Figs. 1 and 9 of 35 the drawings. This telescoping joint in the rod 6 is thus adapted to shorten the rod 6 during the opening and closing operation of the rotating crank arm 9, so as to open door 3 ahead of the door 2, and close door 40 2 in advance of door 3. However, when the crank arm 9 is moved back to closing position, as indicated in Fig. 1, the spring 15 will be placed under tension by the elongation of the rod 6-12 and the tension of 45 the spring 15, under these circumstances, is adapted to facilitate the movement of the crank arm 9, in starting its opening movement from dead center, and has the further advantage that the impact of the joint 11 50 against the telescoping member 12 under the snap of the spring will assist in starting the door 2 if there should be any tendency for the latter to stick.

The crank arm 9 is preferably rotated a 55 half rotation for opening the doors and a half rotation for closing them, the rotation thereof being always in the same direction. The crank arm 9 is preferably formed as part of the double crank arm member with 60 an oppositely extending crank arm 18, the two crank arms forming a horizontally extending bar which is secured to the lower end of a shaft 19, by means of a pin 20, as more particularly shown in Fig. 6. The 65 upper end of the shaft 19, which is adapted

to rotate on a vertical axis is provided with a bearing plate or disc 21, held in place by a cotter pin 22. Bearing bracket plates 23 and 24 are preferably secured together and supported by the ceiling beams 25, to which they are secured by suitable bolts 26, as shown in Figs. 1 and 6 of the drawings. The upper bearing plate 23 is preferably provided with an annular boss 27 having a grooved race, which supports thrust bearing balls 28, cooperating with an annular race groove on the underside of the bearing disc 21 to thereby provide a ball thrust bearing for supporting the rotatable crank member 9-18.

The shaft 19 and cranks 9 and 18 may be rotated by any suitable power means, but preferably I provide a drum 29, rotatably mounted about the shaft 19, the latter having bearings in the hub ends 30 and 31 of the drum, substantially as shown in Fig. 6. The hub ends 30 and 31 of the drum 29 preferably rotate in roller bearings 32 and 33, mounted respectively on the bearing plates 23 and 24 between the hubs and the inside faces of cups in the annular bearing rings 27 and 34, the annular bearing 27 having previously been referred to as carrying the balls 28 for the thrust bearing supporting the crank arms 9 and 18.

In order to drive the crank arms 9 and 18 by a rotation of the drum 29, the lower hub 31 of the latter is preferably provided with diametrically opposite ratchet pin sockets 35, in which ratchet pins 36 operate, the pins being thrust outward by springs 37, as indicated in Fig. 6 of the drawings. The ratchet pins 36 cooperate with crown ratchet teeth grooves 38 formed in the upper face of the hub 39, secured to or formed as part of the crank arm 9-18, as shown in Fig. 8. The ratchet teeth or pockets 38, in the present instance, slope upward counter-clockwise, so that driving engagement is effected between the ratchet pins 36 and the crank arms to rotate the latter clockwise, as viewed in Fig. 1, under the power drive of the drum 29.

The drum 29, in the present instance, is shown as adapted to be rotated clockwise by suitable cables 40 and 41, wound about the lower part of the drum and extending over suitable pulleys to weights adapted to supply the necessary power. In order to increase the effectiveness of the weights, the cables 40 and 41 preferably extend over pulleys 42, secured to the underside of ceiling blocks 43, the cables then passing through pulleys 44 from which the respective weights 45 are suspended. The ends of the cables are then anchored at 46 to the ceiling blocks 43, substantially as indicated in Figs. 1 and 12 of the drawings. By this means, it will be understood that power may be applied to rotate the drum 29 by winding up

the weights and the arrangement is such that the crank arms 9—18 may be rotated a comparatively large number of times, for opening and closing the doors, before it becomes necessary to wind up the weights again.

In order to conveniently wind up the cords or cables 40—41 on the drum 29, and thereby wind up the weights, the surface of the 10 drum is preferably divided into two drum sections by a central flange 47, and a cable 48 (see Figs. 1 and 6) is wound about the upper section 49 of the drum in the opposite direction from the winding of the cords 40 and 15 41, so that by pulling on the cable 48 and unwinding it from the drum 29—49, the cables 40—41 will be wound on to the drum. For convenience in winding up the weights 20 by pulling on the cable 48, the latter preferably passes horizontally outward to the wall of the garage and after passing over a pulley 50, secured to the wall thereof, passes downward and may be pulled directly. Preferably, however, the end of the 25 cable 48 is connected with a "crab" or winch drum 51 and may be readily wound thereon by the handle 52, the arrangement being substantially as indicated in Fig. 1 of the drawings. In winding up the weight by 30 rotating the drum 29, the ratchet pins 36 will ride over the ratchet teeth grooves 38, which will prevent reverse rotation thereof, no ratchet mechanism being required in connection with the "crab" 51.

35 In order to hold the crank arm member 9—18 against rotation by the drum 29, there is provided an escapement dog 53 (see Figs. 1 and 6) pivotally mounted in a bracket 54 secured to one of the ceiling beams 25 by 40 suitable bolts 55, as shown in Fig. 6. A spring 56 connected with a dog rock arm 57 is adapted to hold the dog 53 in position to engage one or the other of the crank arms 9 and 18, and prevent rotation thereof. 45 When the escapement dog 53 is rocked upward on its pivot 58, it will be moved out of engagement with the crank arm and the latter will be permitted to rotate under the drive of the weights acting on the drum 29. As soon as the escapement dog is operated to release one of the crank arms 9—18, and thereafter restored to normal position by the spring 58, it will engage the other crank arm and stop rotation of the crank 50 arm member. In order to cushion the blow in stopping the rotating crank arms by the escapement dog 53, a suitable cushion or shock absorbing device is provided. In the present instance each of the crank arms 9 and 18 is provided with a hollowed out portion 59 on its engaging edge, which is 55 covered by a flat leaf spring 60, substantially as indicated in Fig. 7 of the drawings, which it will be seen will serve as a shock absorber or cushioning device.

It will be seen that the mechanism thus far described is adapted to operate the doors of the garage for opening and closing the same by moving the escapement dog 53 out of engagement with the respective crank 70 arms 9 and 18. As shown in Figs. 1 and 6, it will be seen that when the doors are closed, the crank arm 9, to which the links 6 and 7 are pivotally connected, is in engagement with the escapement dog 53. Releasing the escapement dog will, therefore, permit the drum 29 to rotate the crank arm 9, around to the position shown in Fig. 9 to open the doors, and the crank arm member will be stopped in this position by the engagement of the crank 18 with the escapement dog 53. Again upon releasing the escapement dog 53, the crank arm member will rotate another half revolution and bring the crank arm 9 back into engagement with the escapement dog, thereby closing the doors, as represented in Fig. 1. In order to facilitate operation of the escapement dog 53 from various convenient points, the rock arm 57, connected therewith, is preferably 80 connected by a cable or link 61 (see Fig. 1) with an intermediate rock lever 62 pivoted in a bracket 63, secured to one of the ceiling beams 25. The object of the rock lever 62 will be more particularly pointed out 85 later.

To provide means for operating the escapement dog 53 from a post located in front of the garage, the pull rod or cable 61 may be extended, but preferably the rock lever 100 62 is connected by a suitable cable or cord connection 64 to a bell crank lever 65, pivotally mounted on a bracket 66 secured to the top side-rail of the garage, as shown in Figs. 1 and 2. The other arm of the bell crank 105 65 is connected by means of a cable or cord 67 (Fig. 2) with a bell crank 68, pivotally mounted in a bearing bracket 69 embedded in the floor of the garage near the corner thereof, as indicated in Figs. 1 and 9 of 110 the drawings. The bearing bracket 69 is preferably secured to the end of a pipe 70 extending under the front wall of the garage and under the driveway to a similar bearing bracket 71 (see Figs. 10 and 11), which 115 pivotally supports a bell crank 72. A cord or cable 73 extends from the bell crank 68 through the pipe 70 to the bell crank 72, one arm of which projects into a hollow post 74, in the base 75 of which the bearing 120 bracket 71 is embedded.

The box-like post 74 is preferably formed of wall planks, secured to strips of metal 76 and 77, formed as rectangles or squares, conforming to the cross sectional shape of the hollow post. The lower metal strip 77 is preferably made of angle iron and secured to the base member 75 in any suitable manner. The side walls or planks of post 74 may be secured to the metal strips 76—77 130

in any suitable manner, such as by clips 78. One wall 79 of the hollow post, facing the center of the driveway is preferably provided with a hinged door 80 which is adapted to swing vertically inward and downward on hinges 81 as shown in Fig. 11.

The door 80 is connected by means of a link 82 with one arm of a bell crank lever 83 pivotally supported in a bracket 84 mounted on the opposite wall of the post, the other arm of the bell crank 83 being connected by a cable or link 85, with the outwardly projecting arm of the bell crank 72, which, as previously pointed out, is connected by suitable links or cables to the rock arm 57 of the escapement dog 53, the arrangement being such that by pushing the door 80 inward, the escapement dog 53 will be lifted to release the crank arm 9, for opening the doors.

Obviously, it is desirable to prevent unauthorized persons from opening the garage, and, therefore, the door 80 is preferably provided with a key operated lock 86, the bolt 87 of which is adapted to cooperate with a keeper 88, secured to an upper cross strip of the post which forms the door jamb, substantially as shown in Fig. 11. It is apparent that it may be desirable, at times, to get at the connections within the post 74, and, for this purpose, the top 89 thereof is preferably formed as a lid being hinged at 90, and latch hooks 91 are provided for holding the lid or top of the post secured in closed position. The latch hooks 91 are preferably so placed that by unlocking the door 80 and pushing it inward, the hooks may be reached to unlatch or latch them when necessary.

It is desirable to provide for actuating the escapement dog 53, from within the garage and for this purpose, another cable or cord 92 is preferably connected to the rock lever 62, and anchored at 93 to the front wall of the garage, as shown in Fig. 1. The cable 92 being near the ceiling, a cable or cord 94 attached at 95 near the middle of the cable 92, passes over a pulley 96 and down toward the floor, so as to hang in convenient position to be reached and pulled by anyone entering the small side door 97 of the garage, so as to actuate the escapement dog, substantially as shown in Fig. 4 of the drawings.

When the car is driven out of the garage, it is desirable to close the doors and lock up the place, and to avoid the necessity of getting out of the car for this purpose, a long cable or cord 99 is passed through an eye 100 in the cable or cord connection 92 and drops down in position for the handle 101 (see Fig. 4) to be grasped by a person in the car as the car moves out of the garage. The rear end of the cord or cable 99 preferably extends over a pulley 102, secured to

one of the ceiling beams 25, the end of the cord being secured to a weight 103, for drawing the cord or cable 99 back into the garage after it has been carried out through the door as the car moves out on the driveway. A button 104 secured on the cord 99 is provided for engagement with the eye 100 when the cord is drawn out, thereby exerting a pull on the cord or cable 92 to operate the escapement dog 53 and permit rotation of the crank arms to close the doors.

The connecting rods 6 and 7 secured to the respective doors 2 and 3 of the garage, acting in conjunction with the crank arm 9, when the latter is at dead center, are adapted to lock the doors so that they cannot be opened from the outside, but it is desirable to provide a supplemental bolt 105 slidably supported on the lower inside of one of the doors (3) by the usual bracket 106, as shown in Figs. 4 and 5. This bolt 105 cooperates with a keeper socket 107 in the floor of the garage for securing the door in closed position. In order to draw the bolt 105 when the doors are to be opened, the rock lever 62, previously referred to as being operated by cords or cables 64 and 92, to actuate the escapement dog 53, is connected by means of a link or cable 108 with a bell crank 109, pivoted in a bracket 110, secured to the plate beam 111, above the doors. The other arm of the bell crank 109 is connected by a link 112 with a hook 113, slidably mounted in a bracket 114, the lower end of the hook being adapted to engage an overhanging lug 115, on the end of a slide bolt 116, connected with the bolt 105, by a link 117, substantially as shown in Figs. 4 and 5 of the drawings. The lug 115 and bolt 116 are held in proper cooperative relation with the hook 113 by a bracket support 118, secured to the upper edge of the door 3 in line with the bolt 105 at the bottom thereof. By this arrangement, it will be seen that operating the cables 64—92—61 to operate the escapement dog 53 to open the doors, will also, through the rock lever 62, operate the link or cable 108, to lift the latch bolt 105 and unbolt the lower ends of the doors.

It is believed that the operation of my improved garage door operating mechanism will be fully understood from the foregoing, from which it will be seen that the operator on entering the garage can pull the cord 94 and the doors will be opened. Then upon getting into the car and driving it out of the garage, the handle 101 of the cord 99 will be grasped and carried along as the car moves out onto the driveway, thereby lifting the weight 103 and finally bringing the button 104 into engagement with the eye 100, which should occur when the car has cleared the doors sufficiently for them to close. The final pull on the cord 99, when the button 104 engages the eye 100 will operate the es-

capement dog 53, which is now in engagement with the crank arm 18, to release the crank arm member for closing the doors. As soon as the escapement dog has been released, the end of the cord 99, held by the person in the car, should be released and the weight 103 will jerk or draw the cord back into the garage before the doors have completely closed. When the car comes to the garage, the operator comes up on the driveway and without getting out of the car, inserts a key in the lock 86, and pushes the door 80 inward, thereby releasing the escapement dog 53 and permitting the weight 15 driven drum to operate the crank arm 9 to open the doors. After arriving within the garage, a pull on the cord 94 will again operate the escapement dog 53, and the crank arm member will rotate back to the position shown in Fig. 1 and close the doors.

It will be understood that while I have shown the rotating crank arms 9 and 18 as operating two doors, the same mechanism, obviously, can be utilized for opening a single door. Furthermore, my door operating mechanism has been shown and described in connection with a single garage, but it will be understood that a double garage may be similarly equipped in duplicate and operated from a single post in front of the garage, if so desired.

I wish it to be understood that while I have shown the preferred form of my improvement, I do not wish to be limited to the specific details of construction shown for obviously, various modifications therein may be made by those skilled in the art, without departing from the spirit and scope of the invention.

40 I claim:—

1. In a garage door operating mechanism the combination with a horizontally swing-

ing door, of bearing plates secured to the garage ceiling beams, a shaft supported by said bearing plates to rotate on a vertical axis, a crank arm secured to and rotating with said shaft, a connecting rod pivotally connected directly to and between the door and said crank arm, power means for rotating said crank arm, the arrangement being such that a complete rotation of the crank opens and closes the door, and a manually releasable holding dog successively engaging said crank arm for preventing the rotation thereof under the action of said power means.

2. The door operating mechanism as claimed in claim 1, in which manually operable pull cords are provided for operating said holding dog to release said crank arm for rotation by the power means to thereby operate the door.

3. In a garage door operating mechanism, the combination with a pair of horizontally swinging doors, of bearing plates supported by the ceiling beams of the garage, a shaft supported by said bearing plates for rotation on a vertical axis, a bar forming a pair of horizontal oppositely extending crank arms secured on the lower end of said shaft, a pair of connecting rods pivotally connected to one of said crank arms and to the respective doors, a drum rotatably supported by said bearing plates, a cable connected to said drum for rotating the same by a weight, connecting means between said drum and the crank arms, whereby rotation of the drum by the weight is utilized for rotating said crank arms, a manually controlled detent dog adapted for directly engaging said crank arms successively to prevent rotation thereof, by the drum, and pull cords for operating said detent.

GEORGE T. VAN HORN.
